DESIGN FOR AN ARM FOR A LIGHTING-FIXTURE.

60,117.

Specification for Design.

Patented Dec. 27, 1921.

Application filed January 5, 1921. Serial No. 435,274. Term of patent 7 years.

To all whom it may concern:

Be it known that I, GOTTFRIED WESTPHAL, a citizen of the United States, residing in Lakewood, Ocean county, and State of New Jersey, have invented an Ornamental Design for an Arm for a Lighting-Fixture, of which the following is a specification, reference being had to the accompanying drawing, forming a part hereof.

In the drawing—

Figure 1 is a side view of an arm for a fixture showing my new design.

Fig. 2 is a top view of the arm.

I claim:

The ornamental design for an arm for a lighting fixture, substantially as shown.

This specification signed this fifteenth day of December, 1920.

GOTTFRIED WESTPHAL.
